CASE LINER

Harry M. Hanson, Shelbyville, Ind., assignor to
 The Kennedy Car Liner & Bag Co., Shelbyville,
 Ind., a corporation of Indiana

Application June 14, 1937, Serial No. 148,148

3 Claims. (Cl. 229—58)

This invention relates to case liners.

It has for one of its objects the provision of a foldable liner the bottom portion of which is an integrally folded piece forming bottom and sides with seamless corners, associated unitarily with a tubular member forming the upper sides of the case liner.

Another object of the invention is to provide a case liner of the type described in which the bottom member is telescoped into the tubular member, the latter being folded beneath the edges of the bottom member and being adhered thereto so as to constitute a reinforcement for all lines of fold of the lower portion of the liner.

Other objects of the invention will appear as the following description of a preferred and practical embodiment thereof proceeds.

In the drawing throughout the several figures of which the same characters of reference have been employed to designate identical parts:

Figure 1 is a perspective view of the tubular member of the case liner of the present invention, viewed from beneath;

Figure 2 is a perspective view of the bottom member of the case liner viewed from above;

Figure 3 is a perspective view from beneath of the assembled case liner in expanded condition;

Figure 4 is a perspective view of one end of the case liner in folded condition; and

Figure 5 is a fragmentary sectional view through the case liner when in expanded condition.

Before advertizing to a detailed description of the invention, it will be understood that the object of case liners is to protect the valuable contents of the cases from damage in storage or transportation due to the seepage of dust, dirt, and particularly moisture. Before the advent of the present invention, the conventional case liner consisted of flat bottom portion to which the sides or tubular portion were adhesively attached. A pasted seam was thus present all around at the level of the bottom which when subjected to dampness would seep, giving free access of moisture to the contents of the case.

Referring now to Figure 2, it will be understood that the bottom or tray member 1 therein depicted consists of a sheet of flexible material such, for example, as paper which may be water-proofed or not, according to the utilization to which it may be subjected. It is folded upon four sides to form a flat bottom 2 with integral sides and ends 3 and 4 respectively. The corners are folded in without cutting as indicated at 5 so as to produce seamless corners for the full height of

the tray. Where waterproof material is employed a thoroughly impervious receptacle is thus provided which does not rely upon joined parts either pasted or otherwise secured for its structural integrity.

The tubular member 6 shown in Figure 1 is of parallelepipedal form when expanded and is of such size as to closely embrace the bottom member 1 when the latter is inserted within it. The tubular member 6 is folded to form the side and end flanges 7 and 8, respectively, which underlie the bottom 2 of the tray 1 when the latter is pushed down to its fullest extent into the tubular member, as is illustrated in Figure 3. Preferably those surfaces of the tubular member and tray which contact one another are pasted together, thus to form a double wall reinforcement for the folded corners and bottom edges of the tray member.

The entire case liner thus formed is foldable in usual manner into flat condition. First, both sides 9 and 10 of the tubular member are folded inwardly until they come together on the center line 11 of the bottom. This forms the outwardly extending triangular portions 12, see Figure 4. Those portions of the two side members 9 and 10 which are congruent are then folded to one side of the center line of the bottom as illustrated in Figure 4 and the triangular portion 12 together with the coincident portions of the sides adjacent thereto are folded along the line 13 against the bottom forming a flat package. The case liner is expanded in the manner of an ordinary bag.

By the selection of a blank of proper size, the sides of the integrally folded tray member 1 may be of any desired height.

While I have in the above description defined what I believe to be a preferred and practical embodiment of the invention, it will be understood to those skilled in the art that the specific details of construction and arrangement of parts as shown and described are by way of example and not to be construed as limiting the invention as defined in the appended claims.

What I claim is:

1. Case liner comprising a tray member integrally folded to provide a bottom, sides and seamless corners, and a tubular member forming a depthwise extension of the sides of said tray member, said tubular member fitting the bottom dimensions of said tray member into which said tray member is inserted, said tubular member having in-folded flanges at its lower end underlying and contacting the bottom of said tray member, said flanges forming reinforcements for the

peripheral lines of fold defining the bottom of said tray member.

2. Case liner comprising a foldable bag including a tray member integrally folded to provide a bottom, sides and seamless corners, and a tubular member forming a depthwise extension of the sides of said tray member, said tubular member fitting the bottom dimensions of said tray member and into which said tray member is inserted, said tubular member having in-folded flanges at its lower end underlying and contacting the bottom of said tray member, the contact-

ing surfaces of said tray member and tubular member being adhesively united.

3. Case liner comprising a tray member integrally folded to provide a rectangular bottom and sides, and seamless corners, and a rectangular tubular member fitting the bottom dimensions of said tray member and within which tubular member said tray member is secured, said tubular member extending beyond the bottom of said tray member, adapted to protect the under peripheral margin of the bottom of said tray member. 5 10

HARRY M. HANSON.
